CONDIMENT RECEPTACLE CADDY

Edward N. Montesi, Barrington, R.I., assignor to Dart
Industries Inc., Los Angeles, Calif.

Filed Jan. 15, 1973, Ser. No. 323,692

Term of patent 14 years

Int. Cl. D7—06

U.S. Cl. D7—58

FIG. - 1

FIG. - 5

FIG. - 4

FIG. - 2

FIG. - 3

FIG. - 6

FIG. - 7

FIG. 1 is a top front perspective view of a condiment receptacle caddy showing my new design;

FIG. 2 is a side view thereof;

FIG. 3 is a rear elevation view thereof;

FIG. 4 is a top plan view thereof;

FIG. 5 is a partial cross sectional view taken along line 5-5 in FIG. 2;

FIG. 6 is a cross sectional view taken along line 6-6 in FIG. 2;

FIG. 7 is a partial cross sectional view taken along line 7-7 in FIG. 2;

FIG. 8 is a cross sectional view taken along line 8-8 in FIG. 3; and

FIG. 9 is a cross sectional view taken along line 9-9 in FIG. 3.

I claim:

The ornamental design for a condiment receptacle caddy, substantially as shown.
